ELECTROPLATING ANODE AND MOUNT

Angelo Zanetti and Leonce C. Testut,
New York, N. Y.

Application June 21, 1946, Serial No. 678,179

1 Claim. (Cl. 204—224)

(Granted under the act of March 3, 1883, as
amended April 30, 1928; 370 O. G. 757)

1

This invention relates to electroplating and in particular to an anode for use in plating both main and crank-throw journals of crankshafts.

In numerous instances it is desirable and necessary to maintain machine parts and the like at substantially predetermined dimensions by periodic coating or plating thereof. For example, when crankshaft journals are worn until they no longer meet the minimum specified tolerances, the journals are chrome plated to increase their diameters.

For uniform plating, the anode must be below the surface to be plated; therefore in plating a crankshaft the crankshaft must be rotating so that the plating is concentric with the surface of the journal. The anode must also be held close to the journal to be plated. Crankshaft journals have been chrome plated previously with a roller type anode but occasionally short circuits occurred causing the surface of the journal to be burned. Also the plating was sometimes uneven and was not always deposited on the fillets of the shafts. With use of the new anode of this invention the percentage of shorts and burns is greatly reduced; the plating is much more even; and the plating is readily deposited on the fillets and cheeks of the shafts.

An object of this invention is to provide an apparatus for the plating of journals of crankshafts.

Another object is to provide an anode and anode holder for use in plating worn main and crank-throw journals of crankshafts.

Further objects and advantages of this invention, as well as its construction, arrangement and operation, will be apparent from the following description and claim in connection with the accompanying drawings, in which:

Fig. 1 is a front elevation of the anode according to one form of the invention.

Fig. 2 is a side elevation of the anode shown in Fig. 1.

Fig. 3 is a cross-sectional view of the carrier of the anode shown in Fig. 1 taken along the line 3—3.

Fig. 4 is a cross-sectional view of the anode shown in Fig. 1, taken along the line 4—4.

Fig. 5 is a perspective view showing a crankshaft supported in a rack with the anodes attached.

As shown in Figs. 1 and 2, the anode generally designated 20 consists of a lead anode member 11 suspended from a cross arm 12, which is welded to a guide rod 13 and a carrier 14. The carrier 14 is attached to, but insulated from, guide rod

2

13 by means of insulating material 21 and carrier 14 rides on, but is insulated from, the journal to be plated by means of glass pins 15 and 16. The glass pins 15 and 16 keep the anode member 11 centrally located with respect to the cheeks of the crankshaft 18 and at a fixed clearance from the cheeks and the surface of the journal to be plated. The four pins 15 are normal to the surface of the journal and maintain the radial clearance between anode member 11 and the journal. The four pins 16 are at a 45° angle to the diameter of the journal, as shown in Fig. 3, and maintain axial clearance between the anode member 11 and the cheeks of the crankshaft 18.

15 As shown in Fig. 4, the lead anode member 11 has a number of vent holes 17 drilled through it to permit free passage of the plating solution and the gases formed during the plating process. The carrier 14 has large vent holes 17a in it, as shown in Fig. 2.

20 Because the shape of the anode is important in connection with the securing of uniform deposits, the anodes are carefully formed over accurate dies, the anodes that are to be used for journals 25 of the same shape and size being formed on the same die. In this way similar journals of a single crankshaft 18 when plated from anodes so made, have deposited thereon equal amounts of plating.

25 In chrome plating the journals of a worn crankshaft 18, the entire surface except the journals to be plated is painted with a chrome-resistance paint; then crankshaft 18 is suspended by its extremities in a rack 19, as shown in Fig. 5. The anodes 20 are then clamped around the journals 30 to be plated and a tank (not shown), surrounding the crankshaft 18, is filled with the plating solution so that the surfaces of the solution is above the crankthrow journals at their highest position. The guide rods 13 of the anodes 20 ride in a slot 35 in a wooden beam 22 so that the anodes are insulated from the rack 19 and are held upright as the crankshaft 18 rotates. Braided copper leads 40 23 are attached to the upper ends of the guide rods 13 of anodes 20. These leads connect to the rheostat (not shown) that controls the current 45 to the anodes. To cause the crankshaft to rotate during the plating operation, an electric motor 24 mounted on rack 19 drives a sprocket-drive unit 25 through a reduction gear 26, the other end of 50 this sprocket drive being connected to crankshaft 18.

55 It is to be understood that various modifications and changes can be made in this invention without departing from the spirit and scope thereof as set forth in the appended claim.

The invention described herein may be manufactured and used by or for the Government of the United States of America for governmental purposes without the payment of any royalties thereon or therefor.

What is claimed is:

An electroplating device comprising a carrier having a surface exposed to an axis, a plurality of vitreous insulating anti-friction locating elements extending toward the axis from said surface and terminating at radially-equal distances from the axis, some of said pins extending radially and some extending at about a 45° angle to the axis, an insulating member on said carrier remote from said surface, a conductive support mounted on said member and insulated from said carrier, said support having spaced portions extending on opposite sides of the axis, and an electrode fastened to said spaced support portions, said electrode being on the opposite side of the axis from said carrier and below the axis, said electrode between said portions having a surface exposed to the axis, the intersection of said electrode surface and a plane normal to the axis forming an arc about the axis as a center of less than 180° and concave toward the axis, the intersection of said

electrode surface and a plane including the axis forming an arc concave toward the axis.

ANGELO ZANETTI,
LEONCE C. TESTUT.
